CONSTRUCTION BLOCK SUPPORT
Lauren Meigs, Elka Park, N.Y. 12427
Filed Oct. 4, 1966, Ser. No. 584,123
7 Claims. (Cl. 52—603)

This invention relates to construction blocks, and in particular to an improved support means for construction blocks.

Masons and bricklayers have long experienced problems in laying construction blocks which are customarily made from cinder. In particular, much time is spent to assure that a newly laid block remains level after having been deposited on top of a layer of fresh cement or mortar. The heavy block often tends to sink in one corner or at one end and before continuing to lay another block the mason must be certain that the one previously laid remains level and true. This is, quite obviously, unproductive as it detracts from the time which may more profitably be spent in laying new blocks.

In an attempt to reduce the tendency of the blocks to settle masons have increased the consistency of the mortar or cement. This practice often results in a poor joint between the blocks since cement adheres best when it is wet and of a consistency which is not sufficient to support equally the weight of the block.

To eliminate such problems those skilled in the art have constructed blocks having means for supporting the blocks until the cement or mortar has sufficiently hardened. Thus blocks have been constructed with protrusions to support the block on the top surface of a previously laid block. Such supports have taken many forms including channeled members running the width of the block, peg-like protrusions located at each corner, or dowel members inserted in holes provided in each corner of the block. However, in those instances where the protrusion supports have been fabricated of the same material as the block they have been susceptible of breakage either during transportation to the job site or when being used in construction. The dowel-like inserts have not completely solved the problem as they often tend to become canted in their holes which then results in the block assuming a non-horizontal position.

The primary object of the invention is to provide a simply constructed support means that is inexpensive to produce and operate that obviates the above-mentioned difficulties.

A further object of this invention is to provide an improved support means for construction blocks that will enable such blocks to be laid readily and efficiently in an exactly level and horizontal position.

The foregoing and other objects, features and advantages of the invention will be apparent from the following more particular description of a preferred embodiment of the invention, as illustrated in the accompanying drawings.

In the drawings:

FIGURE 1 is an inverted view of a construction block showing the bottom side and illustrating the support means;

FIGURE 2 shows a preferred embodiment of an insert support means;

FIGURE 3 illustrates the manner in which the improved support means are used in a typical application.

In accordance with the invention, a recessed slot is provided at each of the four corners of the bottom side of a construction block. An insert is pressed into each of the recessed slots. The insert comprises the support means and has a rotatable support member which is mounted on a pivot member. Locking means are provided across the bottom of the insert to engage the rotatable support means

2

when it is rotated into a fully vertical or upright position. The rotatable support members are rotated and automatically locked into an upright position at the site of the construction by hand. When all of the support members are rotated and locked into position the construction block is ready to be placed in position and cemented.

FIGURE 1 shows the bottom side of a standard construction block in accordance with the invention illustrating the improved support means. The cinder block 12 is molded according to standard processes with a recessed slot 14 in each of the four corners. These slots may be made with a slight modification of existing molds. Recessed slots 14 are each approximately 1" long, 1/2" wide, and 1/2" deep. The edges of each recessed slot 14 are located approximately 1/2" from the outer edges of construction block 12. Rotatable support members 16 are shown locked in operating position so that they are vertical with respect to the bottom of construction block 12. In operating position support members 16 extend approximately 1/2" above the bottom surface.

An enlarged view of insert means 18 is shown in FIGURE 2. Insert 18 may be made of any material, metal or plastic, but it is preferred that a deformable material having substantial rigidity such as plastic be used. When made of a deformable plastic material insert 18 will tend to be anchored in recessed slot 14 since it can be constructed to be force fit into recess slot 14. Insert 18 is preferably of the same dimensions as recessed slot 14, but of such dimensions to provide a snug and secure fit 30 within recessed slot 14.

Support members 16 are made of either metal or plastic and are preferably 1/8" thick and 1" long. The ends of support members 16 extending above the bottom surface of the construction block are preferably rounded to prevent their being caught on the surfaces of the construction block supporting them to enable the construction blocks to remain relatively freely movable. Support member 16 is securely mounted to rotatable shaft 20 midway along its length. Shaft 20 is rotatably mounted to the sides 40 of insert means 18, for example, by extending shaft 20 through holes in the side members of insert means 18.

Locking means 24 is positioned across the bottom of insert 18 as shown in FIGURE 2. Locking means 24 serves to hold support member 16 in a vertical position and lock it there. Locking means 24 may comprise a slit along the bottom of insert means 18 into which the edge of support member 16 is forced when rotated into a vertical position. Those skilled in the art will recognize that any suitable locking means will suffice to hold support member. For example, if it is desired to make insert means 18 without a bottom, then locking means 24 may comprise shaft-like member having a slit along its length to accommodate the engaging edge of support member 16. When in locked position, support member 16 is approximately 1/2" above the edge surfaces of insert means 18 and the bottom surface of construction block 12. Inserts 18 are preferably mounted in recessed slots 14 with the uppermost edges flush with, or slightly below, the surface of construction block 12.

In FIGURE 3 two courses of construction block 26, 28 are shown to illustrate the use of support members 16. The first course 26 is laid and leveled. Mortar or cement is then placed on top of the blocks forming course 26. The blocks forming course 28 are then placed on top of the mortar and the blocks forming course 26 with support members 16 locked in their vertical or upright position. The mortar has been omitted from the figure for the sake of clarity. Support members 16 prevent the construction blocks from tilting or settling before the cement has had a chance to form and support the blocks itself.

While the invention has been particularly shown and

described with reference to a preferred embodiment thereof, it will be understood by those skilled in the art that various changes in form and details may be made therein without departing from the spirit and scope of the invention.

What is claimed is:

1. A construction block having a bottom surface, comprising:

a plurality of recessed slots located on the bottom surface, a plurality of insert means, individual ones of said insert means being mounted in individual ones of said recessed slots, each of said insert means including rotatable support members mounted in said insert means and extending above the surface of said construction block when in a fully upright position for supporting said construction block, said insert means further including locking means for securing said support member in said fully upright position.

2. A construction block according to claim 1 wherein an individual one of said recessed slot and said insert means are located in each corner of said bottom surface.

3. A construction block according to claim 2 wherein said insert means further includes rotatable shaft means mounted to said insert means, said support members being mounted to said shaft means.

4. A construction block according to claim 3 wherein each of said recessed slots and insert means are rectangular in shape and essentially 1" long, $\frac{1}{2}$ " wide and $\frac{1}{2}$ " deep.

5. A construction block according to claim 4 wherein said support member is of rectangular shape having an

upper edge and a lower edge, said locking means being in the form of a slit along the bottom of said insert means, said slit having an opening to receive and secure said lower edge when said support member is rotated into a vertical upright position.

6. A construction block according to claim 5 wherein the upper edge of said support member has rounded corners.

7. An insert member for mounting within a recessed slot in a construction block, comprising:

a rectangular shaped box frame, support means rotatably mounted on said frame, said support means being rotatable from a substantially horizontal position to a substantially vertical position, locking means mounted within said frame for securing said support means when in a vertical position, a portion of said support means extending above the top of said frame when said support means is in a vertical position.
